UNITED STATES PATENT OFFICE.

CARL GEORGE CARLBERG, OF OMAHA, NEBRASKA.

GRADING-MACHINE.

1,228,530.

Specification of Letters Patent. Patented June 5, 1917.

Application filed September 21, 1916. Serial No. 121,391.

To all whom it may concern:

Be it known that I, CARL GEORGE CARLBERG, a citizen of the United States, residing at Omaha, in the county of Douglas and 5 State of Nebraska, have invented certain new and useful Improvements in Grading-Machines, of which the following is a specification.

This invention relates to an improvement 10 in grading machines adapted for use upon comparatively large areas of ground, and has for one of its objects to provide means for plowing, scooping and elevating the ground, said means being used and actuated in connection with the engine of a motor vehicle, the stresses for the most part being directed substantially at right angles to the line of travel so that the vehicle may be of comparatively light weight.

15 The invention includes the combination with an engine-driven vehicle, of a carrier frame mounted upon and adapted to have an intermittent movement longitudinally thereof, an endless carrier provided with 20 plows and movable in a cycle transverse to the line of travel of the vehicle, an endless, inclined conveyer, and a scoop or scraper arranged to receive the furrow slices from the plows, and to deposit the excavated earth 25 upon the conveyer. The invention also includes the use of a plurality of plows upon a carrier movable horizontally and adapted 30 to engage in the ground at different depths, so that the stresses will not be delivered co- 35 incidently when forming deep furrows.

The invention consists of the novel construction, combination and arrangement of parts as described herein and claimed, and as illustrated in the accompanying drawing, 40 it being understood that changes in form, size, proportion and minor details may be made without departing from the invention, as determined by the appended claims.

In the drawing, Figure 1 is a view in side 45 elevation of the grading machine. Fig. 2 is a view of the machine in longitudinal section, on line 2-2 of Fig. 3. Fig. 3 is a plan view of the machine, the driver's seat, foot boards and upper part of the vehicle frame 50 being removed. Fig. 4 is a transverse section through the carrier frame on line 4-4 of Fig. 3. Fig. 5 is a transverse section through the carrier frame on line 5-5 of Fig. 3. Fig. 6 is a rear view of the machine. 55 Fig. 7 is a detail relating to Figs. 1 and 2,

to show relative position of parts when the scoop or scraper is elevated. Fig. 8 is a detail to show means for shifting the carrier frame, being an end view of one of the cams, the shifting-bar being in longitudinal section. Fig. 9 is a detail relating to Fig. 1 for clearly showing certain gears. Fig. 10 is a detail showing a keyway and key respectively for the operating shaft and a sprocket wheel.

60 Referring now to the drawing, the invention is illustrated in connection with a vehicle which may be propelled by any suitable power, as the engine shaft 1 adapted to rotate the rear axle 2 since the engine shaft is provided with a gear wheel 3 (Fig. 2.) 65 engaging the gear wheel 4 of the line shaft 5, said shaft 5 having bearings in the vehicle frame 6 and being provided at its rear end with the bevel gear 7 engaging a bevel gear 8 of the stub shaft 9 upon which is mounted a sprocket wheel 10, a sprocket chain 11 being employed for engaging the wheel 10 and engaging a sprocket wheel 12 upon said rear axle.

70 In order that furrows may be formed substantially at right angles to the line of travel while the vehicle is moving forwardly, and to provide a mounting for certain mechanism for this purpose, a carrier frame is provided and shown herein as a platform 13. 75 As best shown in Fig. 5, it is slidably mounted at its opposed sides in the side bars *a* of the vehicle frame, the tongues *b* of the platform engaging in the grooves *c* of the side 80 bars, this mounting operating to resist movements vertically but permitting movements of said platform longitudinally of the vehicle frame.

85 In order that the platform or carrier frame may remain stationary while the plows engage the ground and while the vehicle is moving forwardly said platform is provided with a pair of forwardly projecting shifting-bars 14, each being provided 90 with a slot 15 (Fig. 8.). At 16 (Fig. 3.) is indicated a transverse shaft upon which is mounted a pair of cams 17 each being provided with a tooth *d* (Fig. 8.). A rotatable movement for the shaft 16 is provided by 95 means of its bevel gear 18 engaging the bevel gear-facing 19 of the spur gear 20 of the shaft 21, said shaft 21 and the gear 20 being rotated by means of the spur gear 3 of the engine shaft, the teeth *d* of the cams 100 105 110

simultaneously entering the slots 15 and engaging the shifting bars 14 for moving the carrier frame forwardly.

At 22, near one of the sides of the vehicle, 5 is an operating shaft journaled in the vehicle frame and carrier frame, its front end being provided with a bevel gear 23, said shaft, between its ends, being provided with a keyway 24 (Fig. 10.); and upon said shaft 10 is mounted a sprocket wheel 25, its hub being provided with a key 26 engaging in said keyway. At 27, near the opposite side of the vehicle, is indicated an idler shaft disposed parallel with shaft 5, 21 and 22 and 15 having bearings in the vehicle frame and carrier frame, upon said shaft 27 being mounted an idler sprocket wheel 28, a keyway and key, respectively, being provided for said shaft and sprocket wheel similar to that 20 already described for members 22 and 25.

Mounted upon the sprocket wheels 25 and 28 is an endless carrier or sprocket chain 29, upon which are mounted the plows 30, 31 and 32, a suitable underframe 33 being provided with rollers 34 and disposed below and carried by the platform 13 for resisting stresses and for maintaining the plows in the ground when they move below the platform.

30 The sprocket chains move in the direction indicated by the arrows shown in Fig. 4, shaft 22 being rotated by operation of the transverse shaft 63 journaled in the front part of the vehicle frame, said shaft 63 having a miter gear 64 engaging the miter gear 23 and being provided with a toothed gear 65 in engagement with the worm 66 of the engine shaft. In operation the platform 13 will be moved forwardly of the vehicle by 35 action of the cams 17 as described, the plows then being above the platform, and the parts are so proportioned and arranged that the plow 32 will enter the ground when the platform 13 has completed its forward movement.

40 The plows, preferably, are of different sizes so that a single furrow of considerable depth may be formed at each complete or-bicular movement of the endless carrier 29, 45 the plows engaging different horizontal planes in the ground, this being of great advantage since the stresses will be less than the use of a single, comparatively large plow in the formation of a deep furrow; and it 50 will be understood that, while the plows engage in the ground and while the vehicle is moving forwardly, the platform 13 will remain stationary.

Means are provided for removing and elevating the furrow slices which are formed by the plows, consisting, in part, of a scoop or scraper 35 having a length substantially equal to the length of the furrows or platform, said scraper being of angular form in 55 cross-section and consisting of a forwardly

projecting blade *e* and an inclined slide-plate *f*. The ends of the plate *f* of the scraper are pivotally mounted, as indicated at 36, upon the pair of brace-members or hangers 37 which project downwardly from the platform or carrier frame. 70

In order that the scraper 35 may have a swinging movement for depositing the furrow slices upon the endless, inclined conveyer 38 at intervals and immediately after each complete furrow has been formed, mechanism is provided consisting, in part, of the pair of crank-arms 39 mounted upon the transverse shaft 40 which has bearings in the carrier frame, a pair of links 41 being employed and pivotally connected with the crank-arms and scraper 35. Mounted loosely upon the shaft 40 is a pinion 42 adapted to constantly engage the pinion 43, said pinion 42 being under control of a clutch 44 having a collar *g* engaging in the groove or trackway *h* of the wheel 45, said wheel 45 and pinion 43 being mounted on the shaft 46. 75

Shaft 46 is provided at its inner end with a miter gear 47 in engagement with the miter gear 48 of shaft 21. A rotatable movement for shaft 21 is provided by means of its pinion 20 being in engagement with the pinion 4 as heretofore explained. As best shown in Fig. 9 it will be seen that the shaft 21 is 95 provided with a keyway 49, the miter gear 48 being provided with a key 50 engaging in said keyway, which permits the gear 48 to slide on the shaft 21 and permits the gears 48 and 47 to remain in engagement when the 100 carrier frame is shifted forwardly of the vehicle.

Since the scraper is mounted upon the platform 13 it will have a movement forwardly of the vehicle simultaneously with the forward movement of all other parts upon the platform, including the plows. The parts are so proportioned and arranged for their movements that the blade *e* of the scraper 35 will be disposed adjacent to the 110 plows, and in the same plane as the bottom of the largest plow, when the plows engage in the ground, the result being that the furrow slices formed by the plows 32, 31 and 30 will be deposited upon said blade *e* while 115 the endless carrier 29 is moving in somewhat less than one half of its cycle.

As soon as the plows pass from the lower side of the platform, the crank-arms 39 will swing in an arc substantially of 30 degrees 120 to incline the plate *f* for causing the loose earth thus elevated to slide rearwardly and downwardly upon the endless conveyer 38, said swinging movement of member 35 being caused by the temporary engagement of the 125 pinion 42 with the pinion 43, said pinion 42 being under the control of the clutch 44 as explained. The groove or trackway *h* of the wheel 45 has a suitable curvature for causing a comparatively rapid swinging movement 130

in an upward direction of the crank arms 39 to cause the loose earth to be discharged to the conveyer 38 and to then immediately swing downward to dispose the blade upon the excavated part of the ground, as shown in Fig. 2, and during the forward movement of the platform the blade *e* will slide upon that part of the ground from which the earth has been removed and will operate to 10 scrape the surface of the ground when sliding forwardly.

Having fully described the parts which effect the plowing, any further explanation relating to their operation is not considered necessary. Since the furrows are formed transverse to the line of travel, the vehicle may be, comparatively of light weight, and therefore less than ordinary power will be required for operation. In the practical use 20 of the invention, the speed at which the vehicle may be driven is a matter of no importance since the speed for the endless carrier 29 will correspond thereto. The plows, of course, may have any suitable width to form 25 wide or narrow furrows. The parts which control the movement of member 29 are so proportioned that the plow 30 will enter the ground, during the forward movement of the vehicle, approximately as soon as the carrier frame, by operation of the cams 17, has been shifted forwardly, and it will be understood that, during the period required for 30 the three plows to form the single, deep furrow, the miter gear 48 will remain in engagement with the miter gear 47, the key 50 sliding in the keyway 49 of shaft 21, the carrier frame or platform remaining stationary until the plow 32 has completed its furrow.

While any suitable construction may be 40 provided for the conveyer 38, I have shown and prefer to employ two endless belts *m* and *n*, each being provided with cross-strips. For moving the belts, a horizontal, transverse, rotatable shaft 51 is employed, said 45 shaft having bearings in the inclined frame *k*, and actuated by means of the rotatable shaft 9 heretofore mentioned, the shaft 9 being provided with a miter gear 52 in engagement with the miter gear 7, and a sprocket wheel 53 being loosely mounted on 50 shaft 9; also a sprocket chain 54 being provided and mounted upon the sprocket wheel 53 and upon a sprocket wheel 55 of shaft 51. At 56 is indicated a shaft having bearings 55 in the upper part of the frame *k*, said shaft being provided with a sprocket wheel 57, and by means of a sprocket chain 58 in engagement with the sprocket wheel 57 and a sprocket wheel 59 upon the shaft 51, the endless belt *n* may be moved.

As best shown in Fig. 6, the bevel gear 7 of the driven shaft 5 is constantly in engagement with the two bevel gears 8 and 52, the engagement of said gear 7 with the gear 52 65 causing the rotation of shaft 9 upon which

the sprocket wheel 53 is mounted for moving the belts *m* and *n* as above described, and since the gear 8 is loosely mounted on shaft 9, its direction of rotation will be reverse to the direction of rotation of the gear 8.

As best shown in Figs. 1 and 7, a hopper 60 is provided for the lower end of the frame *k*, upon which the loose earth is deposited by the scraper 35, and the parts are 75 so proportioned and arranged for the movements of the platform 13, that at the time the scraper is swung upwardly, the rear side of the scraper will be disposed in engagement with the front edge of the hopper 80 so that approximately all of the loose earth will be deposited upon the hopper and upon the belts to be conducted upwardly, and from thence to fall upon the inclined slide 61, this slide having any suitable inclination 85 and being disposed transversely of the vehicle. As shown in Fig. 2, idler shafts 62 may have bearings in the conveyer frame and may be provided with sprocket wheels or pulleys, as shown, to sustain stresses directed to the conveyer belts.

What I claim as my invention and desire to secure by Letters Patent is,—

1. A grading machine, comprising, in combination with a forwardly movable vehicle, a carrier frame mounted upon and adapted to have an intermittent movement substantially parallel with the line of movement of the vehicle, a movable, endless carrier mounted upon and encircling the carrier frame, plows mounted on the carrier for forming furrows transverse to the line of movement of the vehicle, an inclined conveyer mounted on the vehicle, a scraper member mounted on the carrier frame arranged to have a swinging movement in one direction for receiving the furrow slices from the plows and to have a swinging movement in a reverse direction for depositing the furrow slices upon the conveyer.

2. A grading machine, comprising, in combination with a forwardly movable vehicle, a carrier frame mounted upon and adapted to have an intermittent movement longitudinally of the vehicle, a movable, endless carrier mounted upon and encircling the carrier frame, a plurality of plows of varying dimensions mounted on the carrier and adapted to be disposed in alignment during a part of the movement of said carrier for forming furrows transverse to the line of movement of the vehicle, an actuated, inclined conveyer on the vehicle, and a scraper member mounted on the carrier frame movable in one direction to receive the furrow slices when formed by the plows and movable in an opposite direction to deposit the furrow slices upon the conveyer.

3. A grading machine, comprising, in combination with an engine-driven vehicle,

an endless carrier movable by the engine, plow-members mounted on the carrier for excavating the ground while disposed in horizontal alinement at substantially right angles to the line of travel of the vehicle, means on the vehicle for elevating the ground which has been excavated, said plow members projecting outwardly from the endless carrier at varying distances therefrom to form furrows of different depths.

4. An excavating machine, comprising, in combination with a forwardly movable vehicle, a carrier frame on the vehicle, an endless, movable carrier encircling the carrier frame and normally movable with the vehicle, plow members mounted adjacent to each other on the carrier for forming furrows in the ground, means to permit the carrier frame to remain stationary while the plows are forming furrows, means to cause a movement of the carrier frame forwardly of the vehicle after the plow members have formed the furrows, and devices actuated for elevating the furrow slices from the ground.

5. A grading machine, comprising, in combination with an engine-driven vehicle, a carrier frame on the vehicle, mechanism actuated by the engine for shifting the carrier frame forwardly of the vehicle, an endless carrier on the carrier frame, a plow member mounted on the carrier with its bottom projecting outwardly therefrom, secondary plow members each having a less dimension than the first named plow member, said endless carrier being movable by actuation of the engine for disposing the plow members below the carrier frame during a part of its movements, an endless, actuated conveyer on the vehicle, a scraper member mounted on the carrier frame formed angular in cross-section to provide a blade and a slide-plate, mechanism actuated by the engine for moving the scraper in one direction to dispose the blade in a plane substantially at the bottom of the furrow to receive the furrow slices while the plows are disposed below the carrier frame, and mechanism actuated by the engine for moving the scraper in a reverse direction for depositing the furrow slices upon the conveyer.

6. An excavating machine, comprising, in combination with a forwardly movable vehicle, a carrier frame on the vehicle, an endless carrier normally movable with the vehicle and movable in an orbit around the carrier frame transversely of the movement of the vehicle, plow members on the carrier disposed in alinement with reference to each other for engaging in the ground, means to permit the carrier frame to remain stationary during the forward movement of the

vehicle while the plows are in engagement with the ground, and means to cause a movement of the carrier frame forwardly of the vehicle after the plow members are disengaged from the ground.

7. A grading machine, comprising, in combination with an engine-driven vehicle, a carrier frame mounted upon the vehicle and provided with a pair of shifting bars, an endless carrier movable by actuation of the engine, said carrier being mounted upon and encircling the carrier frame, plows mounted on the carrier for forming furrows transverse to the line of movement of the vehicle, mechanism actuated by the engine for elevating the furrow slices formed by the plows, and a pair of cams actuated by the engine for engagement with the shifting bars to cause a movement of the carrier frame forwardly of the vehicle after the furrows have been formed.

8. A grading machine, comprising, in combination with an engine-driven vehicle, a carrier frame on the vehicle, mechanism actuated by the engine for shifting the carrier frame forwardly of the vehicle, an endless carrier on the carrier frame, a plow member mounted on the carrier with its bottom projecting outwardly therefrom, secondary plow members each having a lesser dimension than the first named plow member, said endless carrier being movable transversely of the line of movement of the vehicle by actuation of the engine for disposing the plow members in alinement below the carrier frame to form furrows, and means actuated by the engine for elevating the furrow slices formed by said plow members.

9. A grading machine, comprising, in combination with an engine-driven vehicle, a carrier frame mounted thereon, an endless carrier movable by actuation of the engine, said carrier being mounted upon and encircling the carrier frame, a plurality of plow members of varying dimensions mounted on the carrier and adapted to be disposed in alinement during a part of the movement of said carrier for forming furrows transverse to the line of movement of the vehicle, devices actuated by the engine for elevating the furrow slices formed by the plow members and mechanism actuated by the engine for moving the carrier frame forwardly of the vehicle.

In testimony whereof, I have affixed my signature in presence of two witnesses.

C. GEORGE CARLBERG.
